Specification for Design.

Patented Aug. 30, 1921.

Application filed March 5, 1920. Serial No. 363,576. Term of patent 14 years.

To all whom it may concern:

Be it known that I, JOHN H. LICKERT, a citizen of the United States, residing at Evanston, in the county of Cook and State of Illinois, have invented a certain new, original, and ornamental Design for a Carver-Fork, of which the following is a specification, reference being had to the accompanying drawing, forming a part thereof.

The drawing shows Figure 1 is a plan view, Fig. 2 is a side elevation; and Fig. 3 is an end elevation of a carver fork showing my new design.

I claim:

The ornamental design for a carver fork as shown.

JOHN H. LICKERT.
